FINGER SUCKING PREVENTIVE DEVICE
Walter Baron, 28 Bayville Park Blvd.,
Bayville, N.Y. 11709
Filed July 12, 1965, Ser. No. 471,236
4 Claims. (Cl. 128—133)

ABSTRACT OF THE DISCLOSURE

A finger sucking preventive device formed of two strips of adhesive material arranged in parallelism whereby respective interior adhesive sides thereof are opposingly arranged in spaced superposed relation, a plurality of slat elements disposed between said strips and arranged transversely with respect to the length thereof, said elements being in mutually spaced parallelism and adhering to the respective interior sides of said material, the exterior surface of one of said strips being substantially coated with adhesive.

This invention relates to finger sucking deterrents for children and more particularly to a new and useful device of such nature which may be conveniently applied peripherally of one or more fingers of a child and which will destroy any satisfaction otherwise experienced through finger sucking to the end of eliminating the practice thereof.

Whereas the objections to finger sucking, especially where perpetrated by infants, are numerous, the primary object of this invention is to curtail this rather prevalent habit, and thus to preclude malformation of facial features by avoiding deformation or irregularities of the teeth, to preserve the aesthetic value of normal tooth development and to eliminate the inferiority behavior pattern often associated with finger sucking.

Accordingly, and consonant with the foregoing, the instant invention has for an object the provision of a finger sucking preventive device which is provided with slats having air passages therebetween, whereby any vacuum otherwise created during the practice of finger sucking will be destroyed to the end of removing the pleasure normally derived by such practice.

Another object of the present invention is to provide a device of the foregoing character which will be capable of positive and secure application to any finger of an infant and which will not interfere with the normal use of the fingers when applied.

A further object of the invention is to provide an anti-finger-sucking device which is non-toxic and otherwise safe to use.

Another general object of the present invention resides in the provision of a device of the described character which will be simple in structure, economical of manufacture, easily and quickly installed and highly effective in use.

Other objects and advantages of the instant finger sucking preventive device will be set forth in part hereinafter and in part will be obvious herefrom, or may be learned by practice of the invention, the same being realized and attained by means of the structure defined and pointed out in the appended claims.

The accompanying drawings referred to herein and constituting a part hereof, illustrate one embodiment of the invention, and together with the description, serve to explain the principles of the invention.

FIGURE 1 is a perspective view of the finger sucking preventive device illustrated in the unapplied elongate state;

2

FIGURE 2 is an illustrative view of the device according to the present invention applied to two fingers of the hand;

5 FIGURE 3 is a side elevational view of the device illustrating the arrangement of adhesive strips and slat elements;

FIGURE 4 is a plan elevational view of the device in partial cross-section, taken along line 4—4 of FIGURE 3;

FIGURE 5 is a perspective view of the device illustrating the configuration thereof when in the applied operative position;

FIGURE 6 is an end view of the device in the form shown in FIGURE 5; and

15 FIGURE 7 is a cross-sectional view taken along line 7—7 of FIGURE 4.

Referring now in detail to the present preferred embodiment of the invention illustrated in the accompanying drawings, the finger sucking preventive device designated generally by numeral 1 will be seen to comprise two strips of flexible adhesive material 2 and 4 arranged in parallelism whereby opposingly faced sides 6 and 8 are disposed in spaced superposed relation. A plurality of slat or spacer elements 10 are disposed between said strips or lengths of flexible material 2 and 4 and are secured to said material by means of adhesive coatings 12 and 14 which are provided surfaceely of said strips 2 and 4, respectively, as shown in detail in FIGURE 3 of the drawings. As shown in FIGURE 4, said slat elements 10 are arranged transversely with respect to the longitudinal dimension of said strips and are disposed in mutually spaced parallelism as shown.

It will be further observed that the exterior surface 16 of flexible length 4 is coated with adhesive material.

Accordingly, by dint of the arrangement of said slat elements as aforescribed, air passages or channels 18 are provided intermediate said flexible lengths of strip material and between said spacer slats. Therefore, it will be appreciated that upon applying said device peripherally of a finger as shown in FIGURE 2, the development of suction will be prevented where the child draws upon his finger which has been inserted into his mouth. That is, said air passages 18 establish air vents between the finger and the mouth to thereby preclude the formation of any pleasurable sucking sensation otherwise experienced by the child in the absence of the present device about his finger. It has been observed that where the sucking sensation is incapable of effectuation, the finger sucking practice will be discouraged and ultimately the undesirable habit will be eliminated entirely.

50 The flexible strip material is preferably composed of conventional adhesive tape material although other suitable flexible material capable of receiving an adhesive coating as described may be utilized. The spacer slat elements are preferably constructed of plastic which is non-toxic 55 such as styrene and which cannot splinter. Hard wood, however, and other suitable materials may also be used in forming the slats.

As shown, strip 2 extends substantially beyond the end of strip 4, to provide an overlap portion 20 having the adhesive coating 12 exposed on one side. Thus, when applied to a finger, portion 20 will overlap end 22 of the device and be secured thereto, inclined surfaces 24 and 26 being complementary to provide a smooth lapped joint as shown in FIGURES 5 and 6 of the drawings.

When applied, adhesive coating 16 will secure the device securely to the finger and the smooth, overlapped securement of the ends thereof will act to preclude removal thereof through any initial persistent sucking attempts of the child.

Although the preferred embodiment of the finger sucking preventive device has been described, it will be under-

stood that within the purview of this invention various changes may be made in the forms, details, proportion and arrangement of parts, the combination thereof and mode of operation, which generally stated consists in a device capable of carrying out the objects set forth, as disclosed and defined in the appended claims.

What is claimed is:

1. A finger sucking preventive device comprising in combination, two strips of adhesive material arranged in parallelism, whereby respective interior adhesive sides thereof are opposingly arranged in spaced superposed relation, a plurality of slat elements disposed between said strips and arranged transversely with respect to the length thereof, said elements being in mutually spaced parallelism and adhering to said respective interior adhesive sides of said material, said device having an adhesive coating on substantially the entire area of one of the exterior surfaces thereof.

2. A finger sucking preventive device adapted to be applied peripherally of a finger, comprising in combination, a pair of flexible material lengths arranged in spaced, parallel relation, a plurality of individual, separated spacer elements disposed between said lengths, said elements being mutually spaced and attached to said strips, and securing means adapted to retain said device in the form of a loop when said device is applied to the finger.

3. A finger sucking preventive device comprising in combination, two strips of adhesive material arranged in parallelism, one strip being slightly longer than the other to provide an overlap portion at one end thereof, one strip having an adhesive coating on one surface thereof, the other strip having an adhesive coating on both surfaces thereof, an adhesive coating of one strip being disposed in spaced superposed relation with respect to an adhesive coating of the other strip, a plurality of slat ele- 30 35

ments disposed between said strips and arranged transversely with respect to the lengths thereof, said elements being in mutually spaced parallelism and adhering to an adhesive coating of each strip, an inclined surface at each 5 end of the device, said inclined surfaces being complementary whereby when seated against each other, a smooth lapped joint is provided, and when so seated, said overlap portion extends therebeyond to reinforce the securing of the device about the finger.

4. A finger sucking preventive device comprising in combination, two strips of adhesive material arranged in parallelism, one strip being slightly longer than the other to provide an overlap portion at one end thereof, one strip having an adhesive coating on one surface thereof, 10 15 the other strip having an adhesive coating on both surfaces thereof, an adhesive coating of one strip being disposed in spaced superposed relation with respect to an adhesive coating of the other strip, a plurality of slat elements disposed between said strips and arranged transversely with respect to the lengths thereof, said elements being in mutually spaced parallelism and adhering to an adhesive coating of each strip.
